TELEVISION

Harold P. Donle, Meriden, Conn., assignor to
Radio Inventions, Inc., a corporation of New
York

Application November 28, 1928, Serial No. 322,360

7 Claims. (Cl. 178—69.5)

In the present state of the art, television or image transmission either by wire or by radio requires some method of synchronizing a certain device at the receiving station usually 5 termed the "scanning disc" with a somewhat similar device at the transmitting station. It is absolutely essential that these scanning devices run in perfect synchronism. Several methods have been proposed to maintain this synchronism.

One method which has been employed is to control or adjust the speed of the motor driving the receiving scanning disc by hand and so endeavor to keep it in step with the transmitter. This method has been found generally unsatisfactory and extremely critical of control.

Another method heretofore employed consists in sending from the transmitter to the receiver synchronizing impulses at a different carrier 20 frequency from that of the image impulses. This method is particularly objectionable in radio transmission as it necessitates the employment of two channels or wave lengths.

It is of course possible to drive the transmitter 25 and receiver from the same A. C. power line but this is not of general utility, because the receivers can seldom use the same line and in fact would usually have to rely upon an independent source of power.

One method of synchronizing, described in my co-pending application, Ser. No. 306,390, filed 30 Sept. 17, 1928, now Patent No. 1,903,986, utilizes, for synchronizing purposes, the line frequency of the television image.

I have discovered, however, that it is possible to transmit, independently, a television signal and a synchronizing signal over one circuit or at one carrier frequency by taking advantage of visual persistence. For example, by transmitting television impulses for a given period of time and then discontinuing this transmission to transmit a synchronizing impulse over the same circuit. During the transmission of the synchronizing impulse the light source at the receiver is interrupted but due to the comparatively sluggish action of the retina no visual sensation is caused by this interruption.

The main object of my invention therefore is to produce a simple inexpensive and reliable 50 synchronizing system requiring but one channel for both image and synchronizing impulses.

Another object is to provide a system in which the energy of the synchronizing impulses is independent of the intensity of the light impulses.

Fig. 1 is a diagrammatic view of a television

system embodying my invention and utilizing radio frequency transmission.

Fig. 2 is a detail view of the transmitting scanning disc.

Fig. 3 is a detail view of the receiving scanning disc and the synchronizer.

Fig. 4 is a diagrammatic view of a modification of the transmitter.

Fig. 5 is a detail view of a modified form of the transmitting scanning disc.

Fig. 6 is a diagrammatic view of a system employing a wire line or channel for the circuit of transmission.

The picture or image to be transmitted is diagrammatically indicated at 10 and may of course represent an actual object or a moving film. The transmitting scanner 11 is driven by a suitable motor 12 and provided with one or more series of apertures 13 arranged spirally and through which the light from the image passes to a light sensitive cell 14. The output of this cell preferably passes through an amplifier 15 and a radio frequency transmitting device 16 provided with a suitable output antenna 17 and so forth.

At the receiving end is located a suitable pick-up antenna 18, and radio receiving and amplifying means 19. The output of this receiver is connected to a suitable light source 20 such as a so-called "neon" lamp.

The scanning disc 21 of the receiving end is provided with a series of apertures 22 corresponding with the apertures 13 in the transmitter disc and is driven by a motor 23 of any suitable type at approximately the speed of the motor 12 so that the image will be visible at 24 either on a screen or through a lens or in a frame as usual in systems of this character.

The synchronizing of the disc 21 with the disc 11 is accomplished through an electro-magnetic system utilizing light actuating impulses derived from the transmitting station. Attached to or rotatable with the receiving disc 21 is an armature 25 having one or more bars 26. A number of electromagnets 27 are arranged to correspond with the number of armature bars 26. The coils of these magnets are connected to the amplifier 28 which in turn is arranged in shunt with a resistance 29 in the receiving circuit.

The transmitting disc 11 is provided with a number of openings 30 corresponding with the number of magnet coils and armature bars.

It will be noted that there are no apertures in the receiving disc 21 in alignment with the armature bars 26.

As the transmitting disc rotates, the picture apertures 13 are successively passed between the picture or source of light and the energizing cell 14. This causes the rapid succession of picture impulses which are amplified and transmitted and received in the usual manner. When one of the openings 30, which may be termed a "synchronizing" opening passes in front of the light source, the cell 14 will receive a very powerful light impulse which is transmitted in the usual manner and over the same channel as the picture impulse. This synchronizing impulse is amplified and energizes the magnets 27 so as to either retard or speed up the receiving disc 21 depending upon the position of the armature bars relative to the poles of the magnets. These synchronizing impulses also tend to light the lamp 20 but as there is no picture aperture in the disc 21 corresponding in angular relation to the position of the magnets 27, there will be no visual indication of the arrival of the synchronizing impulses.

In Fig. 4 I have shown a modified arrangement in which there are two separate cells 14 and 14' respectively, for the picture impulses and the synchronizing impulses. In such an arrangement it is possible to design the cells and sources of light 10, 10', so as to adapt them to their respective functions, namely, picture control and synchronization.

In the form shown in Fig. 5, it will be seen that the disc 35 has the synchronizing openings 36 entirely inside of the group of picture apertures 37. This makes it possible to arrange the picture light source 10 separate from the synchronizing light source 10'.

It will be understood that a receiving disc and synchronizer similar to the one shown in Fig. 3 may be used with a system employing a scanning disc of the type shown in Fig. 5. Light from the receiver light source will of course be cut off by an unperforated portion of the receiving scanner at the instant when the synchronizing impulse is being received.

The arrangement shown in Fig. 6 is intended to typify a wire line of communication in which the conductors 40 constitute the communicating channel connecting the transmitting amplifier 41 with the receiving amplifier 42. Otherwise this system is similar to the foregoing except that of course the constants of the circuits are suitable for wire line transmission rather than for radio frequency transmission.

It will be apparent from the foregoing that the picture impulses of the synchronizing impulses are transmitted over the same channel or circuit and that the synchronizing impulses may be wholly independent of the light intensity of the picture source.

It should be understood that the picture apertures in the transmitting and receiving scanners may be of any suitable size, number and arrangement although preferably in what is commonly termed spiral arrangement, so that the image is analyzed and again synthesized repeatedly and in each instance in the same order.

I claim:

1. A television system comprising a transmitter having a scanner, a receiver having a scanner, with a channel of communication between them, independent means for rotating said scanners and means utilizing the same channel of communication for automatically synchronizing the receiving scanner independently of the light value of the transmitted image, said

transmitting scanner having a train of apertures adapted to scan the complete picture area and also having a larger aperture, said receiving scanner having a train of image apertures similar to the apertures in the transmitting scanner and a non-perforated portion corresponding to said larger aperture, said larger aperture and said non-perforated portion being similarly located with respect to the trains of picture apertures in the respective scanners.

2. In a television receiver a light source, a scanning member having a train of picture apertures and a non-perforated portion for screening said light source after the completion of a train of picture impulses less than the total number of impulses required for reproducing a complete image and greater than the number required for producing a single line thereof, a motor for driving said scanning member and a synchronizer for said scanning member including an electro-magnetic system having one member moving at a speed always proportional to the speed of the scanning member.

3. The method of synchronizing television systems which includes alternately scanning a series of discrete paths, said series of paths being scanned successively and each path of said series being scanned without interruption thereof, the total length of said series being greater than any linear dimension of the image to be transmitted, interrupting the scanning and transmitting a synchronizing signal over the same channel of communication, said series of discrete paths being in sum less than the totality of paths necessary for a complete scanning of the image to be transmitted.

4. Television apparatus comprising a transmitter having a scanner with a plurality of apertures, a receiver having a scanner with a plurality of apertures corresponding to the transmitter apertures, most of which are for scanning the subject and at least one of which is not for scanning but cooperates with a synchronizing light source, a channel of communication between the transmitter and the receiver, said receiving scanner having an opaque spot corresponding with each aperture cooperating with the synchronizing light source and having electro-magnetic means receiving its energizing impulses over the same channel communication for synchronizing the receiving scanner at intervals between received groups of image signals, the totality of each group of signals being less than a complete image scanning but an integral fraction thereof and being an integral multiple of the signals required for scanning a single line thereof.

5. A television system including means for transmitting repeated groups of picture signals, each group representing an integral fractional part of the entire picture, said part being formed of a series of immediately adjacent continuously scanned lines of said picture, said series constituting less than a complete picture scanning and means for transmitting synchronizing signals independently of and solely between said groups of picture signals.

6. In a synchronized television system, means for transmitting and receiving a complete image characterized by the division of said image into a plurality of strips, each such strip comprising a plurality of immediately adjacent continuously scanned lines, means for transmitting a synchronizing signal during a finite interval of time only at the completion of transmission of signals corresponding to each of said strips, and

means at the receiver whereby said strips are reconstructed into an unbroken picture.

7. In a television system, means for transmitting signals corresponding to fractional bands 5 of an image, each said band comprising a plurality of immediately adjacent lines succeeding one another without interruption by any synchronizing signal, the transmission of successive bands being displaced in time by the interval required for the transmission of a synchronizing signal at the end of each band, and means at the receiver for compensating for the time-displacement of said bands whereby a correctly reconstructed image is produced. 80
